US00D578791S

(12) United States Design Patent
Shilling et al.

(10) Patent No.: US D578,791 S
(45) Date of Patent:  Oct. 21, 2008

(54) BENCH SEAT

(75) Inventors: Jerry L. Shilling, Syracuse, IN (US);
Kent Weimer, Columbia City, IN (US)

(73) Assignee: Wabash Valley Manufacturing, Inc.,
Silver Lake, IN (US)

() Term: 14 Years

(21) Appl. No.: 29/214,154

(22) Filed: Sep. 28, 2004

(51) LOC (8) Cl. 06-01

(52) U.S. Cl. D6/381

(58) Field of Classification Search D6/334-337,
D6/349, 369, 381, 382, 384, 390, 391, 374,
D6/500-502; 297/232-233, 240, 242, 244-245,
297/445.1, 446.1, 451.9, 452.11, 452.12;
5/12.1

See application file for complete search history.
